UNITED STATES PATENT OFFICE

2,103,195

INSECTICIDE

Howard A. Jones, Washington, D. C., dedicated to
the free use of the People of the United States
of America

No Drawing. Application July 3, 1937,
Serial No. 151,915

8 Claims. (Cl. 260—54)

(Granted under the act of March 3, 1883, as
amended April 30, 1928; 370 O. G. 757)

This application is made under the act of
March 3, 1883, as amended by the act of April
30, 1928, and the invention herein described, and
claimed, if patented, may be manufactured and
used by or for the Government of the United
5 States for governmental purposes without the
payment to me of any royalty thereon.

I hereby dedicate the invention herein de-
scribed to the free use of the People of the
10 United States of America to take effect on the
granting of a patent to me.

My invention relates to a heretofore unknown
compound made from a chemical combination
of rotenone and dichloroacetic acid.

15 The object of my invention is to produce this
new compound which has valuable properties as
an insecticide, and is of considerable importance
in the development of new and shortened meth-
ods for the analysis of materials containing
20 rotenone.

My invention is a new chemical compound
and contains 75.35 per cent by weight of rotenone
and 24.65 per cent by weight of dichloroacetic
acid. The empirical formula of this new com-
pound is therefore $C_{23}H_{22}O_6 \cdot C_2H_2O_2Cl_2$. This new
25 compound would be classified in the art as an
"addition compound", and may also be referred
to as a "solvate". This new compound differs
markedly from all other known addition com-
pounds, or solvates, of rotenone in that it is a
30 compound of rotenone and a strong, or highly
ionized, acid.

I have prepared this new chemical compound
and have found that it possesses distinctly dif-
35 ferent physical and chemical properties from
those of both rotenone and dichloroacetic acid.
The compound crystallizes in colorless, lath-like
crystals, while rotenone crystallizes in flat, hex-
agonal-shaped plates. This compound also dif-
fers chemically from rotenone in that it pos-
sesses an acidic group which may be titrated with
alkali by dissolving the compound in a water-
immiscible solvent such as chloroform and
shaking this solution with water while adding
45 the alkali. Because of this fact the compound
is useful in the development of shorter analytical
procedures for the determination of rotenone.
Rotenone itself does not possess any such acidic
group and cannot be titrated with alkali in this
50 way.

The inventor has already reported in the lit-
erature an addition compound of rotenone and
acetic acid in which the molecular ratio is two
mols of rotenone to one of acetic acid. I have
55 also found that other fatty acids and chlorinated

fatty acids combine with rotenone in this mol.
ratio. Thus propionic acid and alpha-chloro-
propionic acid form compounds in which the
molecular ratio is two mols of rotenone to one
of acid. However, the present compound of ro-
tenone and dichloroacetic acid is entirely differ-
ent from these in the fact that it is the only
one which has thus far been found in which
5 rotenone combines with an acid in a mol. ratio
of one to one. This is particularly advantageous
in the application of this compound to use in
analytical procedures in that a much larger
titer of alkali is obtained than with other com-
pounds in which rotenone combines with acids,
and the resulting methods are correspondingly
more accurate. The fact that dichloroacetic
10 acid is far superior to other fatty acids and
chlorinated fatty acids in solvent power for
rotenone is particularly important from the
standpoint of ease of preparation of the new
15 compound.

Furthermore the fusion of rotenone and di-
chloroacetic acid has resulted in a product pos-
sessing insecticidal properties different from those
possessed by rotenone acting alone, and dichlo-
20 roacetic acid acting alone.

The compound of my invention may be pre-
pared in several ways. It may be produced from
rotenone by dissolving said rotenone in dichlo-
roacetic acid, heating the solution and adding
25 water to obtain a crystalline product therefrom,
said product being my invention.

This addition compound of rotenone and di-
chloroacetic acid is also produced from extracts
of the roots of plants of the genus *Derris de-*
35 guelia, extracts of the roots of plants of the
genus *Lonchocarpus*, extracts of the roots of
plants of the genus *Tephrosia cracca*, or from
extracts of any other plant material containing
rotenone. This is accomplished by dissolving any
40 of the above mentioned extracts in dichloro-
acetic acid, heating the solution, adding a suit-
able quantity of hot water and allowing the
whole to cool. The material which crystallizes
45 out is substantially the product covered by my
invention. The preferred method for the purifi-
cation of the product thus obtained is to dissolve
it in hot dichloroacetic acid, add a suitable
50 quantity of hot water, allow the whole to cool,
and separate the material, which crystallizes out,
by filtration or other similar means employed
to separate substances.

The methods of producing my compound are
illustrated by the following examples:

Example I.—2 grams of rotenone is dissolved

5

in a mixture of 20 cc. of dichloroacetic acid and 5 cc. of water. The solution is warmed to a temperature of 50° C. and 150 cc. of water at the same temperature added slowly with continuous stirring, when crystallization occurs. This mixture is cooled to 20° C. and the crystalline compound filtered off and washed with water at 20° C. until all excess dichloroacetic acid is removed. The crystalline product is dried to constant weight in a current of air at 40° C. The product so obtained is the pure addition compound of rotenone and dichloroacetic acid, which is the product covered by this invention.

Example II.—10 grams of the extract from the roots of *Derris deguelia* sp. is dissolved in a mixture of 25 cc. of dichloroacetic acid and 5 cc. of water. The solution is heated to a temperature of 50° C. and 70 cc. of water at the same temperature added slowly with continuous stirring. This mixture is cooled to 20° C. and the separated material filtered off, washed with water at 20° C. until all excess dichloroacetic acid is removed, and dried to constant weight at 40° C. The product so obtained is substantially the addition compound of rotenone and dichloroacetic acid in an impure state, but possesses insecticidal properties and may be purified by the method outlined above without losing its insecticidal properties.

While I have set forth in the above examples my preferred methods of obtaining this new product, I do not wish to be restricted to them.

Having thus described my invention, what I claim for Letters Patent is:

I claim:

1. A new chemical compound composed of a monomolecular combination of rotenone and dichloroacetic acid.

2. A new chemical combination of rotenone and dichloroacetic acid having the empirical formula $C_{23}H_{22}O_6 \cdot C_2H_2O_2Cl_2$.

3. A process for making a chemical compound of rotenone and dichloroacetic acid, which comprises essentially dissolving rotenone in dichloroacetic acid, adding water and separating the resulting crystalline product.

4. A process for making a chemical compound of rotenone and dichloroacetic acid, which comprises essentially dissolving an extract of the roots of plants of the genus *Derris deguelia* in dichloroacetic acid, adding water and separating the resulting crystalline product.

5. A process for making a chemical compound of rotenone and dichloroacetic acid, which comprises essentially dissolving an extract of the roots of plants of the genus *Lonchocarpus* in dichloroacetic acid, adding water and separating the resulting crystalline product.

6. A process for making a chemical compound of rotenone and dichloroacetic acid, which comprises essentially dissolving an extract of the roots of plants of the genus *Tephrosia cracca* in dichloroacetic acid, adding water and separating the resulting crystalline product.

7. A process for making a chemical compound of rotenone and dichloroacetic acid, which comprises essentially dissolving an extract of plant material containing rotenone in dichloroacetic acid, adding water and separating the resulting crystalline product.

8. An insecticide containing as its essential active ingredient a combination of rotenone and dichloroacetic acid.

HOWARD A. JONES.
